(57) **CLAIM**

The ornamental design for a steamed bun mould, as shown and described.

DESCRIPTION

FIG. 1 is a front elevational view of a steamed bun mould, showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front, left, and top perspective view thereof;

FIG. 8 is a rear, right and bottom perspective view thereof; and,

FIG. 9 is an enlarged view of the portion labeled "9" framed in FIG. 5.

In FIG. 5 and FIG. 9, the circular dotted lines define the boundary of the enlarged view and form no part of the claimed design.

1 Claim, 9 Drawing Sheets
